(57) **CLAIM**

I claim the ornamental design for a LED nail dryer lamp, as shown and described.

DESCRIPTION

FIG. 1 is a perspective view of the preferred embodiment. FIG. 2 is a top plan view of the preferred embodiment.

FIG. 3 is a front view of the preferred embodiment.

FIG. 4 is a rear view of the preferred embodiment; and, FIG. 5 is a left side view of the preferred embodiment, the right side view being a mirror image thereof.

The broken lines shown are included for the purpose of illustrating portions of the LED nail dryer lamp that form no part of the claim.
